OF DAYTON, OHIO, A CORPORATION OF OHIO

LIFTING AND LOWERING MECHANISM

Application filed May 2, 1925. Serial No. 27,386.

This invention relates to lifting and lowering mechanism and more particularly to a lifting jack of the pawl and ratchet type.

One object of the invention is to provide a pawl and ratchet jack with improved means for automatically controlling the pawls to permit the lowering of the load under the control of the operator.

A further object of the invention is to provide such a jack which will be simple in its construction, of a strong durable character and will have no parts which will be readily broken or disarranged so as to interfere with the operation of the mechanism.

Other objects of the invention will appear as the mechanism is described in detail.

In the accompanying drawings Fig. 1 is a rear elevation, partly broken away, of a jack embodying my invention; Fig. 2 is a side elevation of the same, partly broken away and showing the pawls in lifting positions; Fig. 3 is a side elevation of the upper portion of the jack showing the positions of the pawls at one stage of the lowering operation; Fig. 4 is a similar view showing the positions of the pawls at a subsequent stage of the lowering operation; Fig. 5 is a section taken on the line 5—5 of Fig. 2; and Fig. 6 is a section taken on the line 6—6 of Fig. 2.

In these drawings I have illustrated one embodiment of my invention and have shown the same as applied to a lifting jack the main features of construction of which are well known, but it will be understood that the mechanism may take various forms and may be embodied in lifting apparatuses of various kinds without departing from the spirit of the invention.

In that particular embodiment of the invention here illustrated the jack comprises an upright standard 1 having at its lower end a supporting base 2 and having mounted therein a vertical reciprocating lifting element 3 which is provided in its rear edge with ratchet teeth 4. The upper end of this lifting element extends beyond the upper end of the standard where it is provided with a work engaging member or cap 5 on which the load is supported. Pivotally mounted in the rear portion of the standard 1 is a pawl carrier

which is here shown as comprising a hub portion 6 of a lever socket 7 which is carried by trunnions 8 pivotally mounted in bearings 9 formed in the side walls of the standard 1, the lever socket being adapted to receive the usual operating lever or bar. Mounted on the pawl carrier or hub 6 of the lever socket is an actuating pawl 10 which is mounted for movement into and out of operative relation with the teeth of the lifting element and which is so mounted on the pawl carrier that the movement of the lever socket about the axis of the trunnions 8 will impart bodily movement to the actuating pawl in the direction of the length of the lifting element. In the present arrangement the pawl is pivotally mounted in a recess or socket formed in the forward edge of the hub of the lever socket, its axis being spaced a sufficient distance from the axis of the lever socket to permit the desired range of movement of the pawl. Mounted within the standard 1, at a point below the pawl carrier 6, is a second pawl carrier which is here shown as a sleeve or hub 11 mounted on a shaft 12 which is supported in the side walls of the standard. Rigidly secured to this hub or sleeve 11 is a detent pawl 13 mounted for movement about the axis of the shaft 12 into and out of operative relation to the teeth of the lifting element. Suitable spring means acts upon the detent pawl 13 to control the position thereof and means are provided for reversing the action of this spring means so that when in one position it will tend to force the detent pawl into operative engagement with the toothed lifting element and when in another position it will tend to force the pawl away from the toothed lifting element. Preferably the hub or sleeve 11 is provided with a rearwardly extending arm 14 which carries at its rear end an apertured stud 15 which is pivotally mounted and through which extends a rod 16, the rod having sliding movement in the apertured stud. This rod is rigidly mounted at its lower end in a supporting member or carrier 17 and is provided at its upper end with a head 18. Confining between the apertured stud 15 and the head 18 of the rod is a spring 19 which is

coiled about the rod. A similar spring 20 is coiled about the rod between the apertured stud 15 and the supporting member 17. The supporting member 17 is movably mounted and is so arranged that when in one position the lower spring, 20, will be compressed and will act upon the arm 14 and thereby tend to force the detent pawl into an operative position. When the supporting member is in another position the upper spring, 19, will be under compression and will act on the arm 14 in a direction to move the detent pawl into an inoperative position. This movement may be imparted to the supporting member in various ways but, as here shown, it is pivotally mounted on a stud 21 which in turn is eccentrically mounted on the hub of an actuating lever 22 which is pivotally mounted on the standard 1, as shown at 23. The arrangement of the eccentrically mounted stud 21 is such that when the lever 22 is in the position shown in Figs. 1 and 2 the supporting member will be in an elevated position and the lower spring 20 will be under compression, and when the actuating lever is in the position shown in Figs. 3 and 4 the supporting member will be in its lower position and the upper spring 19 will be under compression.

Suitable means are provided for yieldably holding the actuating pawl 10 in operative engagement with the toothed lifting element but this means is of such a character and so controlled during the lowering operation that it will tend to move the actuating pawl into an inoperative position. Preferably the action of this yieldable means on the actuating pawl is controlled by the lever 22 which controls the action of the spring means on the detent pawl. To this end I have here shown the controlling means for the actuating pawl as comprising an arm 24 which is rigidly secured at its lower end to a hub 25 which is mounted on the shaft 12 and which is provided with a rearwardly extending arm 26 having pivotally mounted thereon an apertured stud 27 in which is slidably mounted a rod 28, this rod being rigidly mounted at its lower end in the supporting member 17 and having at its upper end a head 29. Coiled about the upper portion of the rod and confined between the head 29 and the apertured stud 27 is a spring 30 and coiled about the lower portion of the rod and confined between the apertured stud 27 and the supporting member 17 is a second spring 31. The springs 30 and 31 are controlled by the movement of the supporting member 17 in the same manner as are the springs 19 and 20. Consequently when the actuating lever 22 is in the position shown in Figs. 1 and 2 the lower spring 31 will act upon the arm 24 to move the same forwardly. This arm is so connected with the actuating pawl that this forward movement thereof will carry the pawl into opera-

tive relation to the toothed lifting member. In the present construction a pin and slot connection is established between the arm 24 and the pawl 10, the arm having a longitudinal slot 32 into which extends a pin 33 extending laterally from the pawl. When the actuating lever 22 is in the position shown in Figs. 3 and 4 the upper spring 30 will be under compression and will tend to move the controlling arm 24 in a rearward direction and thus carry the actuating pawl into an inoperative position.

The sleeve or pawl carrier 11 for the detent pawl 13 is also provided with a forwardly extending arm 34 on which is pivotally mounted an apertured stud 35 having slidably mounted therein a rod 36, the upper end of which is rigidly secured to an arm 37 which is pivotally mounted at 38 on the hub or pawl carrier for the actuating pawl 10. Confined between the arm 37 and the apertured stud 35 is a spring 39 which is stiffer or of greater strength than the springs 19 and 20, which normally control the position of the detent pawl. The arrangement of the spring 39 and its supporting means is such that when the spring controlling means for the detent pawl is so positioned that it tends to move that pawl into an inoperative position the downward movement of the actuating pawl and its carrier 6 will place the spring 39 under compression and cause the same to act on the pawl carrier or hub 11 so as to move the detent pawl against the action of the spring 19 and into operative relation to the toothed lifting element.

When the actuating lever 22 is in the position shown in Figs. 1 and 2 the several parts of the mechanism are in their lifting positions. The springs 20 and 31 are under compression and tend to hold the detent pawl and the actuating pawl, respectively, in operative relation with the toothed lifting element. As shown in Fig. 2 the lever socket is in its elevated position and it will be apparent that the downward movement of the lever will impart upward movement to the actuating pawl and to the lifting element with which that pawl is in engagement and that during this upward movement the detent pawl will yield to permit the teeth of the lifting element to move past the same. When the actuating lever 22 is moved to the position shown in Figs. 3 and 4 the several parts of the mechanism are moved into their lowering positions, that is, positions in which they will operate to permit the load to be lowered under the control of the operator by the manipulation of the lever socket 7. The springs 19 and 30 are under compression and tend to move the detent pawl and the actuating pawl into their inoperative positions. When the lever socket 7 is in its lowermost position and the actuating pawl 10 in its elevated position, as shown in Fig. 4, the

load will be carried on the actuating pawl and the spring 19 will have moved the detent pawl 13 into an inoperative position. The action of the spring 30 on the actuating pawl will tend to move that pawl out of engagement with the toothed lifting element but this movement will be prevented by the tooth which overhangs the nose of the pawl and thereby prevents the pawl from moving about its axis. With the parts in this position the pressure on the lever socket 7 is relieved so that the weight of the load on the lifting element will move the same downwardly. As the lever socket moves upwardly the spring 39 will be placed under compression and before the actuating pawl reaches the lower limit of its movement the tension of the spring 39 will become sufficient to overcome the action of the spring 19 and the detent pawl will be moved into operative engagement with the teeth of the lifting element and will interrupt the movement of that lifting element and support the weight of the load thereon. The slight further downward movement imparted to the actuating pawl, by the continued upward movement of the lever socket, will move the nose of the pawl out of contact with the overhanging tooth of the lifting element and permit the pawl to be moved about its axis by the action of the spring 30 on the controlling arm 24 and the pawl will be held in this inoperative position during the major portion of its upward movement, which is brought about by the downward movement of the lever socket. During this upward movement of the pawl the compression of the spring 39 is relieved but the detent pawl remains in operative engagement with the lifting element due to the teeth overhanging the nose of the pawl and preventing its movement about its axis. Just before the actuating pawl reaches the upper limit of its movement it engages a yieldable member, such as a spring 40, which forces the same into engagement with the toothed lifting element, against the action of the spring 30, and a slight further upward movement is imparted to the actuating pawl to slightly elevate the lifting element and thus release the detent pawl 13 and permit the latter to be moved by the spring 19 into an inoperative position, thus restoring the parts to the positions shown in Fig. 4, after which the cycle of operations above described is repeated so that the load will be lowered step by step and will be at all times under the direct control of the operator.

I have also provided means for moving the detent pawl into an inoperative position independently of the controlling mechanism above described, when it is desired to release the lifting element and allow it to run down quickly, without control. As here shown, this means comprises a flexible member, such as a chain 41, connected with the pawl 13 and

extending to a point outside the hollow standard 1.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In a lifting apparatus, a standard, a toothed lifting element mounted on said standard, an actuating pawl for said lifting element, means to impart operative movement to said pawl, a detent pawl mounted for movement into and out of operative relation to said lifting element, yieldable means acting on said detent pawl to hold it in an inoperative position during the downward movement of said lifting element, and a controlling device mounted for movement with relation to and acting on said detent pawl during said downward movement of said lifting element to move the same against the action of said yieldable means and into operative relation to said lifting element.

2. In a lifting apparatus, a standard, a toothed lifting element mounted on said standard, an actuating pawl for said lifting element, means to impart operative movement to said pawl, a detent pawl mounted for movement into and out of operative relation to said lifting element, yieldable means acting on said detent pawl to hold it in an inoperative position during the downward movement of said lifting element, and a device mounted for movement with relation to and arranged to be operated by the operating means for said actuating pawl for moving said detent pawl against the action of said yieldable means and toward said lifting element during the downward movement of said actuating pawl.

3. In a lifting apparatus, a standard, a toothed lifting element mounted on said standard, an actuating pawl for said lifting element, means to impart operative movement to said pawl, a detent pawl mounted for movement into and out of operative relation to said lifting element, yieldable means acting on said detent pawl to hold it in an inoperative position during the downward movement of said lifting element, an operable device interposed between said detent pawl and the operating means for said actuating pawl and arranged to be actuated by said operating means during the downward movement of said lifting element to move said detent pawl against the action of said yieldable means and into operative relation with said lifting element, and means for automatically moving said actuating pawl into an inoperative position after said detent pawl has been moved into an operative position.

4. In a lifting apparatus, a standard, a toothed lifting element mounted on said standard, an actuating pawl for said lifting element, means to impart operative movement to said pawl, a detent pawl mounted for movement into and out of operative relation to said lifting element, yieldable means acting on said detent pawl to hold it in an inoperative position during the downward movement of said lifting element, an operable device interposed between and connected with said detent pawl and the operating means for said actuating pawl and acting on said detent pawl during the downward movement of said lifting element to move said detent pawl against the action of said yieldable means and into operative relation to said lifting element, and means for automatically moving said actuating pawl into an inoperative position after said detent pawl has been moved into an operative position, for holding said actuating pawl in said inoperative position during the major portion of its upward movement and for moving the same into an operative position just before it completes its upward movement.
5. In a lifting apparatus, a standard, a toothed lifting element mounted on said standard, an actuating pawl for said lifting element, means to impart operative movement to said pawl, a detent pawl mounted for movement into and out of operative relation with said lifting element, yieldable means acting on said pawls to hold the same normally in operative relation with said lifting element, means for reversing the action of said yieldable means, whereby it will tend to move both of said pawls into inoperative positions, and an operable device interposed between and connected with said detent pawl and the operating means for said actuating pawl and controlled by the downward movement of said actuating pawl when said yieldable means is in its reverse position to move said detent pawl against the action of said yieldable means and into operative relation with said lifting element just before said actuating pawl completes its downward movement.
- 50 6. In a lifting apparatus, a standard, a toothed lifting element mounted on said standard, an actuating pawl for said lifting element, means to impart operative movement to said actuating pawl, a detent pawl mounted for movement into and out of operative relation to said lifting element, spring means acting on said detent pawl to hold the same in an inoperative position during the downward movement of said actuating pawl, a second spring arranged to act on said detent pawl to move the same toward its operative position against the action of the first mentioned spring means, and means controlled by the downward movement of said actuating pawl

to render the last mentioned spring operative.

7. In a lifting apparatus, a standard, a toothed lifting element mounted on said standard, an actuating pawl for said lifting element, a carrier for said pawl, means for actuating said carrier to impart bodily movement to said pawl, a detent pawl, spring means acting on said detent pawl to hold the same out of engagement with the teeth of said lifting element during the downward movement of said actuating pawl, and a device connected with said detent pawl and actuated by the carrier for said actuating pawl to move said detent pawl against the action of said spring means and into engagement with said toothed lifting element just before said actuating pawl reaches the lower limit of its movement.

8. In a lifting apparatus, a standard, a toothed lifting element mounted on said standard, an actuating pawl for said lifting element, means to impart operative movement to said actuating pawl, a detent pawl mounted for movement into and out of operative engagement with said lifting element and comprising a hub, an arm rigidly secured to said hub, a rod extending transversely to and slidably connected with said arm, springs carried by said rod and arranged on the opposite sides of said arm, whereby one or the other of said springs will be under compression according to the position of said rod with relation to said arm, means for controlling the position of said rod, a second arm connected with said hub, a rod extending transversely to said second arm and movable relatively thereto, a spring carried by said last mentioned rod and arranged to act on the last mentioned arm to move said detent pawl against the action of one of the first mentioned springs, and means controlled by the movement of said actuating pawl to place the last mentioned spring under compression.

9. In a lifting apparatus, a standard, a toothed lifting element mounted on said standard, an actuating pawl for said lifting element, a pawl carrier on which said pawl is pivotally mounted, means for actuating said pawl carrier, a detent pawl pivotally mounted for movement toward and from said toothed lifting element and comprising a hub, an arm rigidly secured to said hub and extending from that side thereof opposite said lifting element, a pivoted stud carried by said arm, a rod slidably mounted in said stud and having a head at its upper end, a supporting member rigidly secured to the lower end of said rod, springs confined between said stud and said head and between said stud supporting member, means for adjusting said supporting member with relation to said arm to place one or the other of said springs under compression, a second arm rigidly secured to the hub of said detent pawl, and extending

from that side of said hub opposite the first mentioned arm, an apertured stud pivotally mounted in the last mentioned arm, a rod slidably mounted in the last mentioned apertured stud, a connection between the last mentioned rod and the carrier for said actuating pawl, and a spring mounted on said last mentioned rod between the apertured stud and said pawl carrier and arranged to be placed under compression when said pawl carrier moves in a direction to lower said actuating pawl.

10. In a lifting apparatus, a standard, a toothed lifting element mounted on said standard, an actuating pawl for said lifting element, means to impart vertical movement to said pawl, yieldable means acting on said pawl to move the same into an operative position with relation to said lifting element, a detent pawl, yieldable means acting on said detent pawl to hold the same in an inoperative position while said actuating pawl moves downwardly, and means controlled by the downward movement of said actuating pawl to move said detent pawl against the action of the last mentioned yieldable means and into operative engagement with said lifting element just before said actuating pawl completes its downward movement, thereby causing the further movement of said actuating pawl to release the same from said lifting element and permit it to be moved into an inoperative position by the first mentioned yieldable means.

15. In a lifting apparatus, a standard, a toothed element mounted on said standard, an actuating pawl for said lifting element, means to impart vertical movement to said actuating pawl, a yieldable device tending to move said pawl out of engagement with said lifting element, such movement being resisted by the contact between said pawl and a tooth of said lifting element, a detent pawl, a spring acting on said detent pawl to hold the same out of engagement with said lifting element during the downward movement of said actuating pawl and said lifting element, a normally inoperative spring arranged to act on said detent pawl to move the same against the action of the first mentioned spring and into engagement with said lifting element, and means controlled by the downward movement of said actuating pawl to place the last mentioned spring under compression and thereby cause said detent pawl to engage said lifting element before said actuating pawl has completed its downward movement, whereby the further movement of said actuating pawl will release the same from said lifting element and permit it to be moved into an inoperative position by said yieldable means.

20. In a lifting apparatus, a standard, a toothed lifting element mounted on said standard, an actuating pawl for said lifting

element, means to impart vertical movement to said actuating pawl, a yieldable device tending to move said pawl out of engagement with said lifting element, such movement being resisted by the contact between said pawl and a tooth of said lifting element, a detent pawl, a spring acting on said detent pawl to hold the same out of engagement with said lifting element during the downward movement of said actuating pawl and said lifting element, a normally inoperative spring arranged to act on said detent pawl to move the same against the action of the first mentioned spring and into engagement with said lifting element, means controlled by the downward movement of said actuating pawl to place the last mentioned spring under compression and thereby cause said detent pawl to engage said lifting element before said actuating pawl has completed its downward movement, whereby the further movement of said actuating pawl will release the same from said lifting element and permit it to be moved into an inoperative position by said yieldable means, and means to act on said actuating pawl as the latter approaches the upper limit of its movement and force the same into engagement with said lifting element, whereby the further upward movement of said actuating pawl will slightly elevate said lifting element and release said detent pawl for movement into an inoperative position by said yieldable device.

25. In a lifting apparatus, a standard, a toothed lifting element mounted on said standard, an actuating pawl for said lifting element, means to impart vertical bodily movement to said actuating pawl, yieldable means acting on said pawl to force the same away from said lifting element, a detent pawl, a spring acting on said detent pawl to hold the same out of engagement with said lifting element during the downward movement of said actuating pawl, a second spring connected with said detent pawl, and means controlled by the downward movement of said actuating pawl to place said second spring under compression and cause the same to move said detent pawl against the action of the first mentioned spring and into engagement with said lifting element.

30. In a lifting apparatus, a standard, a toothed lifting element mounted on said standard, an actuating pawl for said lifting element, means to impart operative movement to said actuating pawl, a detent pawl, yieldable means for holding both pawls in operative relation with said lifting element during the lifting operation, means to reverse the action of said yieldable means on said pawls, whereby said yieldable means will tend to move both pawls into inoperative positions with relation to said lifting element during the lowering operation, said actuating pawl being held in engagement with

said lifting element during the downward movement thereof by its contact with the tooth of said lifting element, a spring connected with said detent pawl and arranged to be placed under compression by the downward movement of said actuating pawl, the strength of said spring being greater than the strength of the yieldable means which tends to hold said pawl in an inoperative position, whereby said detent pawl will be moved against the action of said yieldable means and into engagement with said lifting element.

15. In a lifting apparatus, a standard, a toothed lifting element mounted on said standard, an actuating pawl for said lifting element, a pawl carrier on which said actuating pawl is pivotally mounted, means for actuating said pawl carrier to impart bodily movement to said actuating pawl, a controlling arm pivotally mounted on said standard and operatively connected with said actuating pawl to move the same toward or from said lifting element, a second arm rigidly connected with and extending transversely to said controlling arm, a rod slidably connected with the last mentioned arm and having a head at one end thereof, an adjustable supporting member rigidly secured to the other end of said rod, springs confined between said last mentioned arm, said head and said supporting member, respectively, a detent pawl mounted for movement into and out of engagement with said lifting element and comprising a hub, an arm rigidly secured to said hub, a rod slidably mounted in said arm having a head at one end and having its other end rigidly connected with said supporting member, springs confined between the last mentioned arm and said head and said supporting member, respectively, means for shifting the position of said supporting member with relation to said arms, a second arm secured to said hub, a rod slidably connected with said second arm and connected at its upper end with said pawl carrier, and a spring mounted on the last mentioned rod and arranged to be placed under compression when said actuating pawl is moved downwardly.

16. In a lifting apparatus, a standard, a toothed lifting element mounted on said standard, an actuating pawl for said lifting element, means to impart vertical bodily movement to said actuating pawl, a pivoted controlling member operatively connected with said pawl, a spring acting on said controlling member and tending to move the same about its axis and to force said pawl away from said lifting element, a detent pawl mounted for movement into and out of operative relation with said lifting element, yieldable means acting on said detent pawl to hold it in an inoperative position during the downward movement of said lifting ele-

ment, and means acting on said detent pawl during the downward movement of said lifting element to move the same against the action of said yieldable means and into operative relation with said lifting element.

17. In a lifting apparatus, a standard, a toothed lifting element mounted on said standard, an actuating pawl for said element, a pivoted arm having a slot near its free end, a pin carried by said pawl and having sliding movement in said slot, a spring acting on said arm in a direction to force said pawl away from said lifting element, a detent pawl mounted for movement into and out of operative relation with said lifting element, yieldable means acting on said detent pawl to hold it in an inoperative position during the downward movement of said lifting element, and means acting on said detent pawl during the downward movement of said lifting element to move the same against the action of said yieldable means and into operative relation with said lifting element.

In testimony whereof, I affix my signature hereto.

JAMES C. DAWLEY.
